PATENTED JUNE 23, 1908.

J. ROSS.

RIGGER'S TRUCK.

APPLICATION FILED MAY 14, 1907.

UNITED STATES PATENT OFFICE.

JOHN ROSS, OF PHILADELPHIA, PENNSYLVANIA.

RIGGER'S TRUCK.

No. 891,442.

Specification of Letters Patent. Patented June 23, 1908.

Application filed May 14, 1907. Serial No. 373,594.

To all whom it may concern:

Be it known that I, JOHN ROSS, of the city and county of Philadelphia and State of Pennsylvania, have invented an Improvement 5 in Riggers' Trucks, of which the following is a specification.

My invention has reference to riggers' trucks, and consists of certain improvements which are fully set forth in the following 10 specification and shown in the accompanying drawings, which form a part thereof.

The object of my invention is to provide means for moving heavy objects, such as machinery, building material, houses, etc., 15 by such means that they may be easily handled with speedy and accurate transportation at a minimum cost.

My invention more specifically relates to the construction of a single caster truck 20 adapted to support the load, whether said load is close to the ground or at a considerable elevation; and in practice several of these independent caster trucks may be employed with any given load.

25 My invention consists of a base-truck, comprising a frame and a caster wheel, combined with an adjustable turn-table detachably connected with the truck and centered thereon by interlocking parts, a portion of 30 which are on the truck and a portion on the base of the turn-table.

35 My invention also consists of the truck above specified when further combined with one or more adjustable frames having interlocking parts adapted to interlock one frame with another or with the top or bottom of the turn-table and also with the top of the base-truck frame, whereby the turn-table may be supported at an elevation above the base- 40 truck and so as to come directly under the work, or be supported at any other position between the base-truck and the work as the exigencies of the case demand.

45 My invention also comprehends details of construction which, together with the features above specified, will be better understood by reference to the drawings, in which:—

Figure 1 is a side elevation of my improved 50 riggers' truck complete showing one form of adjustment; Fig. 2 is a plan view of the base-truck of the same; Fig. 3 is a perspective view of one of the removable frames therefor; Fig. 4 is a perspective view of the upper portion of 55 the turn-table; Fig. 5 is a perspective view of the lower or base portion of the turn-table;

and Fig. 6 is a side elevation of my improved truck, showing the parts of Fig. 1 arranged in a different order, and with a modified manner of supporting the axle. 60

A is the base-truck, B are the independent adjustable frames for building up the truck to any height desired, and C is the turn-table. The frames B are formed of wood, but the turn-table C is formed of cast metal. The 65 several parts A, B and C are provided with interlocking portions which hold them in proper relative alinement and resist torsional displacement in a horizontal plane. Moreover, the interlocking parts permit the 70 adjustment of the several portions, one to the other, in such a manner that the turn-table may be arranged at the top of the independent frames, as indicated in Fig. 1, or below them and next to the base-truck, as 75 indicated in Fig. 6, or if desired, at any intermediate position, so that complete adaptability of the truck, both as to height or position of the turn-table, is at the command of the rigger to suit any particular character of 80 work which he is required to perform.

Referring to the base-truck A, the two sides A' A' are rigidly secured together at a distance apart by the cross frames A² A² which are bolted to the side frames by means 85 of bolts A³ or otherwise. D is a transverse axle which is journaled in the side frames A'; and secured to this axle is a caster wheel E, preferably of considerable width, so as to prevent the truck from rocking in the direction of this axle. Secured to the axle D, is a notched or ratchet-wheel d. Loosely sleeved upon the axle D, is one end of a hand lever F, provided with a suitable double pawl f for engaging the notched or ratchet-wheel. In 90 the position shown in Fig. 1, the reciprocation of the lever F will cause the truck to move to the right, whereas if the lever is thrust over to the right side of the truck, the other portion of the pawl comes into play 100 and in this case a reciprocation of the lever will make the truck move to the left. Aside from the particular form of pawl and ratchet-wheel shown, any other well-known or suitable form for rotating the axle and the caster 105 wheel E may be employed. The upper part of the base-truck A is provided with two transverse notches formed by the raised central parts G G and by the upward extension of the transverse cross frames A². These notches form interlocking parts on the truck to engage the interlocking parts of the ad-

justable frames B or of the turn-table as the case may be, the former being shown in Fig. 1, and the latter in Fig. 6.

Referring now to the adjustable frames B, it will be seen from Fig. 3 that these frames comprise two side frames B' B' connected by two transverse bars B² B² which are secured in place upon the ends of the side frames by vertical bolts B³. The central portions of the side frames B' are provided on the top with upwardly extending parts H, and on the bottom with downwardly extending corresponding parts I. This provides notches between the parts B² and H on the upper part of the frame which correspond to the notches between the parts A² and G on the base-truck. The cross section of the side frames B' on each side of the parts H and I is such as to snugly fit the notches or spaces between the parts A² and G on the base-truck and form with them an interlock, as clearly shown in Fig. 1. The width and the length of the parts I on the bottom of the side frames B' are such as to snugly fit between the two side frames A' A' of the base-truck, and consequently, these parts I prevent the frame B as a whole from shifting in a direction parallel to the axle of the truck; and this forms an additional interlock between the parts A and B. As all of the frames B are alike and are all properly proportioned one to the other, it is evident that by turning every adjacent frame at right angles to the one upon which it rests, the series of frames will be stacked one upon the other, and all will be interlocked, so that no frame may be twisted or shifted in a horizontal plane relatively to any other frame or to the base-truck. For convenience of illustration, I have shown four of such adjustable frames B, but there may be employed any number, one or more, as desired.

The turn-table C consists of a base part J and a top part K pivoted together in any suitable manner. In the form shown, the base part J is provided with a spherical upper portion J² which is received within a spherical socket K² in the upper part K, so that these two parts are firmly engaged in a transverse direction but permit free rotation of the upper part K upon the lower part J about a vertical axis. The base part J is provided at opposite sides with notches J' of such size as to receive the upwardly extending interlocking parts H of the adjustable frames B or the upwardly extending interlocking parts G of the base-truck, so as to either engage the adjustable frames, as shown in Fig. 1, or the truck, as shown in Fig. 6. It will be seen that the base J itself interlocks with the other portions with which it engages, so that it cannot be twisted or shifted in any horizontal direction relatively to the part on which it rests. The upper part K of the turn-table is likewise provided on opposite sides with

notches K' which are adapted to receive the downwardly extending interlocking portions I of the adjustable frames B when the turn-table is arranged below said adjustable frames, as indicated in Fig. 6. This would also be the case where the turn-table was interposed between a series of adjustable frames, that is to say, when one or more of said frames were below the base part J of the turn-table and one or more of the frames arranged above the upper part K of the turn-table, a condition of which latter use might occur where four or more of these trucks were employed under a load in which the turn-table on three of them was practically adjacent to the under surface of the load, and the fourth turn-table, while being on the same level as the other three turn-tables, was considerably below the load at that point and in which was employed the under-frame to complete the distance between the top of the turn-table and the under part of the load. In this case, all of the turn-tables would be at the same level and the operation of the trucks in connection with the entire work would be more uniform and reliable.

By means of these trucks, power may be applied at any place under the load and any truck may be adjusted under its turn-table to suit the direction in which it is desired to move the load. However, when moving the load in a straight line, as, for example, when moving a house down a street, and when the same is pulled by means of horses or a windlass, it is desirable to lock the turn-table against rotation so that the axle D of the truck is maintained at right angles to the direction of movement. To accomplish this in a simple and positive manner, I provide the upper portion of the turn-table with transverse holes k near its base, and similarly I provide a transverse hole l through the spherical portion J² of the base part of the turn-table. When these holes come into alignment, a bolt L is passed through for the purpose of positively locking them together against rotation. Such a bolt is indicated in Fig. 5, but would not be used excepting in cases where a considerable distance of straight travel was necessary. In place of the employment of this bolt, any other suitable device or means of interlocking the parts J and K may be employed.

Ordinarily, the axle D is supported in rigid bearings in the side frames A' of the base-truck, but in some cases it is desirable that the truck body shall be supported upon springs to relieve the strain on the load. In Fig. 6, I have shown my truck modified in this respect. In this case, the axle D is journaled in boxes r secured to the middle of plate springs R, the ends of which rest against the under portions of extensions of the transverse frames A². In this way, the truck frame or turn-table and the adjustable

frames B are all spring-supported upon the axle and caster wheels. Any other suitable arrangement of spring-support may be employed in place of that shown if so desired.

5 The frames B are of such construction that the several parts of which they are composed may be readily disconnected for shipment; or if desired by loosening the bolts B³ the two side frames B' may be swung together by 10 using the transverse frames B² as radius bars. In their closed position, they would occupy very much less cubic space.

15 While it is cheaper to construct the frame work of the base-truck of wood, it may, if desired, be constructed of metal. By employing wood instead of iron, the truck is also lighter and therefore more easily handled and cheaper to transport to the place where the work is to be done.

20 While I prefer the construction shown, the details may be modified without departing from the spirit of the invention.

Having now described my invention, what I claim, as new and desire to secure by Letters Patent, is:—

25 1. In a riggers' truck, a truck portion consisting of a rectangular frame having raised central portions on two of its sides and upwardly extended portions on the other sides 30 forming interlocking notched portions, a notched shaft, a caster wheel secured to the shaft, and means for rotating the caster wheel.

35 2. In a riggers' truck, a truck portion consisting of a rectangular frame having raised central portions on two of its sides and upwardly extended portions on the other sides forming interlocking notched portions, a transverse shaft, a caster wheel secured to 40 the shaft, and means for rotating the caster wheel, combined with an adjustable frame adapted to be removably supported upon the truck frame and comprising side frames adapted to fit into the interlocking notches 45 in the top of the truck frame and provided with downwardly extending portions adapted to interlock between the side frames of the truck and cross frames for connecting the side frames of the adjustable frame together.

50 3. In a riggers' truck, a truck portion consisting of a rectangular frame having raised central portions on two of its sides and upwardly extended portions on the other sides forming interlocking notched portions, a 55 transverse shaft, a caster wheel secured to the shaft, and means for rotating the caster wheel, combined with a series of independent frames supported one upon the other and the whole series supported upon the truck frame, 60 the said independent frames each being provided with interlocking parts adapted to interlock one with the other and also with the truck frame, so as to prevent relative movement in a transverse direction.

65 4. In a riggers' truck, a truck portion con-

sisting of a rectangular frame having raised central portions on two of its sides and upwardly extended portions on the other sides forming interlocking notched portions, a transverse shaft a caster wheel secured to 70 the shaft, and means for rotating the caster wheel, combined with a series of independent frames supported one upon the other and the whole series supported upon the truck frame, the said independent frames each being provided with interlocking parts adapted to 75 interlock one with the other and also with the truck frame, so as to prevent movement in a transverse direction, and a turn-table resting upon the uppermost independent 80 frame and forming an interlocking connection therewith whereby its base portion is prevented from movement in a horizontal direction relatively to the said independent frames.

85 5. In a riggers' truck, a base truck frame supported upon a caster wheel, combined with an independent two part turn-table structure comprising a base part removably interlocked with the base truck frame 90 and an upper part adjustable upon the base part.

95 6. In a riggers' truck, a base-truck frame supported upon a caster wheel combined with a turn-table having its upper portion adjustable relatively to the truck frame having its base removably interlocked therewith, and one or more independent adjustable frames having top and bottom portions adapted to interlock with both the truck 100 frame and the turn-table whereby the position of the turn-table relative to the base-truck may be varied and the turn-table adjusted to suit the requirements of the work.

105 7. In a riggers' truck, the combination of a base-truck, a series of independent frames resting one upon the other and detachably interlocked one with the other and all supported by the base-truck, a turn-table having its base supported by and interlocked with 110 the uppermost independent frame, and a top frame detachably interlocked with and supported by the top portion of the turn-table.

115 8. In a riggers' truck, a base truck frame supported upon a caster wheel, combined with an independent two part turn-table structure comprising a base part removably interlocked with the base truck frame and an upper part adjustable upon the base part, and removable means for locking the upper 120 part of the turn-table against rotation upon its base part.

125 9. In a riggers' truck, a base-truck frame supported upon a caster wheel combined with a turn-table having its upper portion adjustable relatively to the truck frame having its base removably interlocked therewith, and removable means for locking the upper portion of the turn-table against rotation upon the base portion consisting of a remov- 130

able bolt extending transversely through the said upper and base portions of the turn-table.

10. In a riggers' truck, the combination of 5 a base truck having a caster wheel and provided on its top with upwardly extending interlocking portions, and a two part turn-table consisting of a base part detachably supported upon the base truck and having 10 recesses for receiving the upwardly extending interlocking portions thereof and an upper part adjustably pivoted upon the base part and independent of the base truck.

11. In a riggers' truck, the base-truck having 15 its truck provided with upwardly extending interlocking portions, combined with a turn-table arranged above the base-truck and having a base portion provided with recesses shaped for receiving the upwardly extending 20 portions of the base-truck to form an interlock therewith, and having a top movable portion also provided with interlocking recesses, and an independent frame shaped to interlock both with the upward extensions 25 of the base-truck and also with the recesses of the turn-table, whereby the turn-table and independent frame may be interchanged relatively to the base-truck and maintain the interlocked relation between the three parts.

30. 12. An independent frame for a riggers' truck consisting of a rectangular framework B having opposite side frames B' provided centrally with interlocking projections H, I, and connected by cross bars B² at each end 35 so as to form notches between the said cross bars and projections H.

13. In a riggers' truck, a base truck frame 40 consisting of four frames arranged in pairs and each pair at right angles to the other pair to form an open center, combined with springs connecting the cross frames of one pair, boxes secured to said springs, a shaft journaled in the boxes provided with an irregular end for rotating it, and a roller se-

cured to the shaft arranged between the two 45 pairs of frames.

14. In a riggers' truck, a truck frame having 50 a caster wheel and a shaft journaled in the truck frame for rotating the caster wheel, combined with a series of independent pairs 55 of cross frames each pair being arranged across the adjacent pairs of cross frames and held thereto against rotation in a horizontal plane and all of the series of independent pairs of cross frames being detachably supported upon the truck frame.

15. In a riggers' truck, a truck frame having 60 a caster wheel and a shaft journaled in the truck frame for rotating the caster wheel, combined with a series of independent 65 pairs of cross frames each pair being arranged across the adjacent pairs of cross frames and held thereto against rotation in a horizontal plane and all of the series of independent pairs of cross frames being detachably supported upon the truck frame, and a turn-table 70 resting upon the uppermost independent pair of cross frames.

16. In a riggers' truck, a truck frame having 75 a caster wheel and a shaft journaled in the truck frame for rotating the caster wheel, combined with a series of independent pairs 80 of cross frames each pair being arranged across the adjacent pairs of cross frames and held thereto against rotation in a horizontal plane and all of the series of independent pairs of cross frames being detachably supported upon the truck frame, and a turn-table resting upon the uppermost independent pair of cross frames and having means for locking it against rotation relatively to the 85 cross frames.

In testimony of which invention, I have hereunto set my hand.

JOHN ROSS.
